UNITED STATES PATENT OFFICE

GEORGE E. PICKUP, OF NEWARK, OHIO, ASSIGNOR TO THE WEHRLE COMPANY, OF NEWARK, OHIO, A CORPORATION OF OHIO

TOWEL BAR

Application filed April 3, 1930. Serial No. 441,192.

The general object of the present invention is to provide a stove embodying a new and improved towel bar which does not detract from the appearance of the stove and which therefore may be mounted in an unusually convenient position on the stove.

More specifically stated, the invention has for its object the provision of a towel bar adapted to be used on an ornamented stove body and which normally conforms with and constitutes a part of the stove ornamentation.

Other objects and advantages will become apparent from the following description taken in connection with the accompanying drawings, in which:

Fig. 1 is a front elevational view of a stove embodying the preferred form of the invention.

Fig. 2 is an enlarged fragmental plan view of the stove shown in Fig. 1 with the towel bar in its rear or retracted position.

Fig. 3 is a view similar to Fig. 2 showing the towel bar in its forward position.

Fig. 4 is an enlarged cross sectional view taken along the line 4—4 in Figs. 1 and 2.

For purposes of disclosure the preferred form of the invention is illustrated in the drawings and will hereinafter be described in detail as applied to a particular form of stove, but it is to be understood that this disclosure is not intended as a limitation of the invention to this type of stove, it being contemplated that various changes might be made by those skilled in the art to adapt the invention to other types of stoves without departing from the spirit and scope of the invention as defined by the appended claims.

In the preferred form herein illustrated, the invention is embodied in a solid fuel cook stove having a body 10 of the usual form, including a forward wall 11 and a stationary top frame member in the form of a wall 12. In stoves of this character, and in other forms as well, it is customary to embody a decorative band of polished metal such as nickel, to set off or accentuate certain lines of the stove body.

The stove herein shown is ornamented by means of a polished nickel band designated generally as 13 and extending around the

outer edge of the top wall 12 so as to project downwardly over the joint between the side walls and the top wall. As shown in Figs. 1 and 4, the band 13 is of arcuate cross section and is mounted in inset relation to the top wall 12 so that the upper surface of the band 13 is substantially flush with the upper surface of the stove top 12. This is accomplished by offsetting the top wall 12 downwardly near its edges to provide an upright web 14 (Fig. 4) with a horizontal ledge 15 projecting forwardly from the lower edge of the web 14.

In accordance with the present invention the band 13 is formed in several pieces, including portions 16 and 17 near the opposite ends removably overlying the ledge 15 and secured in position on the stove by means of screws indicated at 18 in Fig. 2, or other suitable means, extending upwardly through the ledge 15 and engaging the portions of the ornamental band. Between the end portions 16 and 17 is a section 20 of the band 13 which is of the same form and finish as the portions 16 and 17 and is substantially rigid due to its arcuate cross sectional form.

In order that the section 20 of the ornamental band may serve either as a part of the stove ornamentation or as a towel bar or rack, the section 20 is mounted on the stove body for movement from its normal inoperative position (Fig. 2) adjacent to the stove body in an operative position spaced forwardly of the stove (Fig. 3). The mounting of the section 20 herein shown is of a sliding character and is so arranged that the section 20 may be entirely removed from the stove for the purpose of cleaning the stove top.

As shown in Figs. 2 to 4, the section 20 has a pair of arms 22 secured thereto near the ends of the section so as to project rearwardly therefrom, the arms being arranged to extend through suitable apertures 23 formed in the upright web 14. Forwardly of the apertures 23, the ledge 14 is grooved as indicated at 24 in Figs. 3 and 4, so that the sliding movement of the arms 22 will be guided by the engagement of the arms with the sides of the groove.

The bottom surfaces of the arms 22, there-

fore, ride in the bottoms of the grooves 24, and to maintain the arms in horizontal position a short upstanding boss 26 (Fig. 4) is provided at the rear end of each of the arms to slidingly engage the lower surface of the top wall 12. Inward sliding movement of the section 20 is limited by the abutment of the inner edge of the section 20 with the upright web 14 and to limit the outward movement of the section a lug 27 is formed on the underside of each arm 22. The lugs 27, which are arranged to engage the rear edge of the ledge 15, are spaced from the ends of the arms 22 as shown in Fig. 4 so that even when the arms have been withdrawn to their outermost positions, the bosses 26 will engage the upper wall 12 at points spaced rearwardly from the ledge 15. Thus the section 20 is effectively supported in all of its positions. When the section 20 has been withdrawn from the stove to the position shown in dotted outline in Fig. 4, it may be used as a towel rack by hanging the towels over the horizontal support thus formed. In order to increase the horizontal clearance between the section 20 and the stove body and thus facilitate the use as a towel rack, the ledge 15 is cut away between the arms 22 as shown at 29 in Fig. 3.

To render the section 20 removable, the inner or rear ends of the grooves 24 are recessed downwardly at an angle as shown at 30 in Fig. 4. It will be noted that there is a slight clearance between the upper surface of the arms 22 and the upper edge of the apertures 23 (Fig. 4) so that by lifting the section 20 upwardly and moving it forwardly the arms 22 may be withdrawn from the apertures 23.

From the foregoing it will be apparent that the invention provides a new and improved towel rack for stoves which is of such a character that it may be mounted in an unusually convenient position. Furthermore, it will be seen that by forming the horizontal member of the rack so as to constitute an ornamental part of the stove, a rack is provided which does not noticeably increase the cost of the stove, since such ornamental members must always be separately formed and attached whether or not they serve the double function of an ornament and a rack.

I claim as my invention:

1. A stove having a body with a top frame member offset downwardly at its forward edge to provide an upright section with a ledge projecting forwardly from the lower edge of said upright section, said upright section having a pair of horizontally spaced apertures formed therein, an ornamental bar extending along said ledge in overlying and concealing relation thereto, a pair of arms fixed on said bar and projecting rearwardly therefrom through said apertures to support said bar for movement to a position spaced forwardly from said ledge, said ledge having

grooves formed therein extending forwardly from said apertures and said arms being arranged to ride in said grooves so as to be guided by the sides of said grooves.

2. A stove having a body with a top frame member offset downwardly at its forward edge to provide an upright section and a forwardly projecting ledge, said upright section having a pair of horizontally spaced apertures formed therein, an ornamental metallic bar extending along said ledge in overlying relation thereto with its rear upper edge flush with the top surface of said top frame member, a pair of arms fixed on said bar and projecting through said apertures to support said bar and permit it to be pulled forwardly from the stove body to form a towel rack, and means on said arms arranged to engage said frame member to limit such outward movement of the bar, said ledge being cut away between said arms so as to increase the horizontal clearance between the bar and the stove body when said bar is in its forward position.

In testimony whereof, I have hereunto affixed my signature.

GEORGE E. PICKUP.
